GARBAGE CAN HOLDER
Edwin E. Anders, 150 N. Commercial,
Aransas Pass, Tex. 78336
Filed Feb. 23, 1966, Ser. No. 529,377
2 Claims. (Cl. 211—71)

The present invention generally relates to a garbage can holder and more particularly such a holder that includes structure for supporting a plurality of garbage cans in stationary position to prevent accidental overturning by cats, dogs, wind or the like.

An object of the present invention is to provide a garbage can holder having a ground inserted type of post together with structural arrangements which supportingly engages the garbage can and also tethers the can lid.

Another object of this invention is to provide a garbage can holder which has an upstanding support peg which engages the handle of the can.

A further object of the present invention is to provide a garbage can holder having spring arms and shelf structure for supporting a plurality of garbage cans.

Still another object of this invention is to provide a garbage can holder which is extremely simple in construction, easy to install, effective in use and relatively inexpensive to manufacture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of the garbage can holder of this invention;

FIGURE 2 is a sectional view taken along section line 2—2 on FIGURE 1; and

FIGURE 3 is a perspective of another form of this invention.

Referring now specifically to the drawings, the garbage can holder of the present invention is generally designated by numeral 10 and includes a wood post 12 or other suitable support post inserted into the ground surface or embedded in concrete or the like.

The holder 10 supports garbage cans 16 having removable lids 18 thereon with the cans 16 having handles 20 thereon and the lids 18 having handles 22 which represents conventional garbage can structure.

Tether lines 24 of a flexible nature are connected to lid handles 22 at one end thereof and to a fastener 26 at the other end with the fastener 26 being attached to the top of post 12.

Mounted on post 12 is a plurality of spacer members 28 and upstanding pegs 30 all constructed of wood material and secured in place by nails 32 or other suitable fasteners. The pegs 32 extend upwardly through handle 20 thus supporting the garbage can 16 in elevated position on or above the ground surface.

FIGURE 3 illustrates a supporting post 40 for supporting cans 42 having lids 44 with handles 46 mounted

2

thereon. The lids 44 are tethered by flexible lines 48 attached to the post 40. A container 50 for a deodorant or insecticide is mounted on the post 40 and supporting shelves 52 are attached to the post 40 and braced by braces 54 to support cans 42.

A plurality of spring type gripping arms 56 engage the cans 42 and are mounted on the post 40 by a connecting portion 58 thereby grippingly engaging the can 42 in the center thereof. The structure of the present invention effectively supports and retains the garbage cans and their lids securely in place against displacement due to animals, wind or the like.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. A garbage can holder comprising an upright support post, a plurality of horizontal shelves mounted around the side of said post to support a plurality of garbage cans in spaced relation to a ground surface, a means of tethering garbage can lids to said post to prevent loss of said lids, said means comprising a plurality of hooks secured around said post and a chain secured at one end to each of said hooks, the other end of each of said chain being secured to a handle of each of said lids, each of said shelves being secured by a brace between said post and the underside of said shelf, a plurality of spring type gripping arms for supporting and retaining said cans to said holder, each of said spring-type arms having an outwardly flared terminal end portion for grippingly engaging the center portion of a garbage can, and a container for receiving a deodorant therein said container being attached to the upper end of said post where it is in the vicinity of a person's head and nostrils when in the neighborhood to attend to garbage matters, all of said shelves being at equal elevation, all of said arms being at equal elevation and all of said hooks being at equal elevation.

2. The structure as defined in claim 1 wherein said post and bracket are constructed of wood with the post being inserted into the ground surface.
